(57) **CLAIM**

The ornamental design for a radiator grille for a vehicle, as shown and described.

DESCRIPTION

This application contains subject matter related to the following co-pending U.S. design patent application:

Application Ser. No. 29/834,202, filed Apr. 11, 2022 and entitled “Radiator Grille For A Vehicle.”

FIG. 1 is a front view of a radiator grille for a vehicle showing my new design;

FIG. 2 is a right, front perspective view thereof;

FIG. 3 is a left, bottom perspective view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof.

1 Claim, 8 Drawing Sheets
